BRAIDING MACHINE CARRIER

Roger W. Hale, Rumford, R. I.

Application February 6, 1935, Serial No. 5,231

6 Claims. (Cl. 96—15)

This invention relates to braiding machine carriers and is for the purpose of accomplishing in a simpler manner the result secured by the construction disclosed in my Patent No. 1,723,159, August 6, 1929.

Braiding machine carriers or members, sometimes termed trackers, which support the yarn supply and travel in circuitous or other raceways, are of various types.

In order that the principle of my invention may be readily understood, I have in the accompanying drawing disclosed the preferred embodiment of braiding machine carrier, and I make reference to my said Patent No. 1,723,159 to make clear one manner of use of the braiding carrier in a braiding machine.

In the accompanying drawing,

Fig. 1 is an elevation of one of the carriers to which my invention particularly relates;

Fig. 2 is an elevation viewed from a position at ninety degrees from Fig. 1;

Fig. 3 is an elevation looking at the inside of the upright portion of the carrier, the bobbin being omitted;

Fig. 4 is a horizontal section on the lines 4—4 of Fig. 2, looking down;

Fig. 5 is an under side view of the bobbin showing the formation for engagement with the single member being of a pawl-like character that replaces the double pawl of my said Patent No. 1,723,159; and

Figs. 6, 7 and 8 are details in side elevation representing three different possible positions of the pawl-like member, namely, the locked position of Fig. 6, the position of ratcheting in one direction only, of Fig. 7, and the position of total disengagement, of Fig. 8.

A braiding carrier is provided with a body portion whereon the yarn supply is carried, generally on a bobbin, and a bearing or guiding surface which cooperates with other parts of the braiding machine, as, for example, the rotating quoits, and the fixed portions of the body structure.

My new braiding carrier may be employed in the type of braiding machine shown in my Patent No. 1,723,159, or it may be used with other types of braiding machines. In such machines are used so-called "quoits" which may be of any suitable construction. The carriers of the machine travel in the raceway provided between the framing and the peripheral edges of the quoits which in practice is provided with a suitable lower formation generally indicated at 3 in the drawing hereof and which is of the form adapted to the particular type of braiding machine with

which the carrier of my invention is employed. In the present embodiment of my invention, the upper part of the formation 3 is relatively large and flat as indicated at 4, being of general elliptical form. Therefrom rises the spindle 5, whereon is received the thread or yarn supply 6. Desirably the thread supply is carried upon a bobbin which may be of usual construction except that its base 7 is furnished with or has secured thereto a part 8 preferably similar to the corresponding part in my said Patent No. 1,723,159, and being therefore provided with circumferentially arranged spaced teeth or formations 9, each of which is shown as parallel sided or slightly converging and adapted for engagement with a single member that takes the place of a so-called double pawl or pair of members of my Patent No. 1,723,159, but accomplishes the purpose of that patent in preventing rotation of the yarn package in a direction that would wind up and thus tend to increase the pull or tension on the strand of yarn causing uneven and constantly varying tension. The structure is such as to insure the feeding of the thread always in a taut condition and preventing overfeeding of the thread and any consequent slackness thereof, and also so to control the direction of rotation of the thread mass as thereby to prevent any strain upon the strand of yarn which may be caused by the tendency of the yarn mass to be caused to rotate in a yarn-winding-up direction by the natural oscillation of the carrier as it rapidly reverses its direction in following the track of the braiding machine in which it is used.

The base member 4 is provided upon its upper face at one end with upwardly extending ears 10 in vertical sockets whereof are positioned the ends of a wire 11 bent into a general hairpin shape providing parallel members desirably circular in cross section, upon which the thread tensioning member hereinafter referred to is applied. Desirably the upper end of the wire 11 is provided with a pigtail or bent wire 12 through which the thread passes.

The thread extends from the package or supply 6 through an eye or guide 13 downwardly about a projection 13', thence upwardly through the hook end 14 of the spindle 5 to the point of use. The guide 13 is provided upon one of the upright members of a wire 11, the parallel members of which receive the tension member 15, here shown as having an upright body part 16 of sheet metal. Upon the outer face of the part 16 is provided the said projection 13' about which the thread is guided. At the upper portion of the

body part the sheet metal is wider and is bent inward as indicated at 11, 17, to provide guides encircling the two upright members of the wire 11. At its lower end, the body portion 16 is shown 5 as having secured thereto a strip 18, the ends of which are bent inward as indicated most clearly at 19 in Fig. 4, so as to encircle the parallel parts of the wire 11. The tension member 15 is normally held down by a coiled spring indicated at 10 20, the upper end whereof is attached to an inward part or formation 21 shown in Fig. 3 as centrally positioned at the upper end of the body portion 16. At its lower end the said coiled spring 20 is suitably secured preferably as disclosed in 15 my said patent. The spring 20 is thus positioned between the parallel members of the wire 11 and protected thereby.

Instead of providing the double pawl structure 20 of my said Patent No. 1,723,159, I have been able after very considerable experimentation to provide a more simplified structure by which the same highly desirable results are secured. This permits me to manufacture the carrier or parts thereof at a less cost while retaining all the advantages of the earlier construction.

As shown most clearly in Figs. 2 and 4, I provide a single member of general pawl-like character indicated at 27. The said member is pivoted on a horizontal pin 28 in the hub or upstanding ear 29 rising from the upper edge of the part 4. The said hub may upon its upper face be provided 30 with a slot to receive the pawl-like member 27 in such manner as to permit its rocking movement. The tail end of the said pawl-like member 27 35 has connected thereto at 30 a wire 31, the upper end 32 whereof is bent about one of the upright portions of the wire 11 as clearly indicated in Fig. 3, so as to be engaged at the proper time by the upper face of the strip 18 of the body part 16 40 in the upward pull of the thread upon the projection 13'.

At its opposite end the said pawl-like member 27 is provided with a head 33 which, as shown most clearly in Figs. 6, 7 and 8, is inclined for a 45 purpose to be hereinafter stated and which is of just a sufficient length to be received between any two next adjacent teeth 9 of the part 8. In other words, the space between the inner edges of any two next adjacent teeth 9 is just sufficient to 50 permit the reception of the head 33 of the pawl 27.

Viewing Figs. 6, 7 and 8, it will be evident that when the pawl head 33 is in position shown in Fig. 6 (which I call the position of complete engagement), the yarn or thread mass or package 55 cannot be rotated upon its axis in either direction. When it is in the position of Fig. 7 (which I call the position of partial engagement), it may be rotated only in a forward direction (that is, in the direction of the arrow, toward the left viewing that figure). When the pawl head 33 is in the position shown in Fig. 8, the yarn or thread mass or package may be rotated in either direction. That is to say, the position represented in Fig. 6 constitutes the locked position, that represented in Fig. 7 permits ratcheting in one direction only (namely, in the direction of unwinding the yarn), and Fig. 8 represents a position of total disengagement of the pawl with the part 8.

The purpose of total disengagement as shown 70 in Fig. 8 is to allow the package of yarn or thread to be turned by the hand of the operator in a direction to wind up whatever surplus or slack yarn or thread may exist between the point of yarn delivery from the package and the braiding 75 point. In other words, in the process of replacing

a spool or package of yarn or thread, very often some slack yarn must be taken up by winding the same on the package. It is therefore desirable to provide some means whereby the operator may (while the machine is stopped) entirely release 5 the package and wind upon it whatever slack yarn exists.

While the machine is in operation, the position of the pawl and ratchet relation as shown in Fig. 8 is never reached since the downward pressure of 10 the tension member 15 upon the strand of yarn or thread transmits, by the strand of yarn or thread to the rotatable package, sufficient energy to cause the package to turn from the position shown in Fig. 7.

It will be understood that in operation there is a carrier (or a plurality thereof) traveling in one direction and a carrier (or plurality thereof) traveling in the opposite direction along the sinuous paths shown in my Patent No. 1,723,159. 20 The travel of the carriers each in a sinuous path is at a very high rate and therefore each carrier is being constantly swung upon a longitudinal axis first in one direction and then in the other, so that if the thread mass 6 is not properly restrained 25 from rotating upon its own axis, it would tend constantly to jerk the thread and either to break the same or result in defective braiding. By holding the thread mass 6 from turning upon its own axis in either direction (namely, when the pawl 30 head 33 is in position of Fig. 6) such jerking is prevented. Whenever the thread becomes sufficiently taut, it pulls upwardly upon the projection 13', and causes the strip or part 18 to be lifted so high that it engages the under side 35 of the wire loop 32, thereby elevating the tail end of the lever 27 and withdrawing the pawl head 33 into the position shown in Fig. 7. This permits the rotation of the yarn package 6 in one direction only, namely, in the direction of the 40 unwinding of the thread. This relieves the undue tension upon the thread and permits the projection 13' to drop again, thus causing or permitting the head 33 of the pawl 27 to re-enter a notch of the part 8, with the result that the thread 45 mass 6 is held from improper movement upon its own axis. An excessive push upward upon the bent part 32 of the wire 31 (which is done manually by the hand of the operator while the machine is stopped), will result momentarily in the 50 movement of the pawl head 33 into the position shown in Fig. 8, thus totally disengaging the pawl head from the part 8 and freeing the thread package 6 for rotation in either direction upon its own axis.

It will be understood from the foregoing description that I have provided a construction in which by the use of a single member, preferably of a pawl-like character, the advantages set forth in my said patent are secured, but in a simpler 60 manner.

Having thus described one illustrative embodiment of the invention, it is to be understood that although specific terms are employed, they are used in a general and descriptive sense and not 65 for purposes of limitation, the scope of the invention being set forth in the following claims.

I claim:

1. A braiding carrier for braiding machines adapted to receive a rotatable thread package, a 70 member having a toothed formation in fixed relation with said thread package, a single member adapted to engage said toothed formation either partially or completely, and acting, while 75 in complete engagement therewith, to prevent

- movement of the thread package in either direction upon its axis and when in partial engagement to permit rotation only in a direction of unwinding of the thread, and means whereby tension upon the thread moves said member to permit rotation of the thread package only in a direction of unwinding of the thread.
2. A braiding carrier for braiding machines adapted to receive a rotatable thread package, a member having a toothed formation in fixed relation with said thread package, a single member adapted to engage said toothed formation, and for that purpose having a portion provided with an upper surface that is upwardly inclined in the direction of the unwinding of the thread from the thread package, whereby said member may in a position of complete engagement with said toothed formation prevent movement of the thread package in either direction upon its axis and in a position of partial engagement may permit rotation thereof only in a direction of unwinding of the thread, and means whereby tension upon the thread moves said member in said second mentioned position.
- 25 3. A braiding carrier for braiding machines adapted to receive a rotatable thread package, a member having a toothed formation in fixed relation with said thread package, a single member adapted to engage said toothed formation, and for that purpose having an operative connection with the carrier and having a part to be moved by the condition of tension upon the thread into partial or complete engagement with said toothed formation, the position of partial engagement permitting rotation of the thread package in a direction of unwinding the thread only, and the position of total engagement preventing rotation of the thread package in either direction upon its axis.
- 40 4. A braiding carrier for braiding machines adapted to receive a rotatable thread package, a member having a toothed formation in fixed relation with said thread package, a single member adapted to engage said toothed formation, and for that purpose having a pivotal connection with

the carrier and a part to be moved by the condition of tension upon the thread, into partial or complete engagement with said toothed formation, the position of partial engagement permitting rotation of the thread package in a direction of unwinding the thread only, and the position of total engagement preventing rotation of the thread package in either direction upon its axis.

5 5. A braiding carrier for braiding machines adapted to receive a rotatable thread package, a member having a toothed formation in fixed relation with said thread package, a single member adapted to engage said toothed formation, and for that purpose having a pivotal connection with the carrier and a part to be moved by the condition of tension upon the thread, into partial or complete engagement with said toothed formation, the position of partial engagement permitting rotation of the thread package in a direction of unwinding the thread only, and the position of total engagement preventing rotation of the thread package in either direction upon its axis, said member being also manually movable upon its pivotal connection into a position of complete disengagement with said toothed formation.

10 6. A braiding carrier for braiding machines adapted to receive a rotatable thread package, a member having a toothed formation in fixed relation with said thread package, a single member adapted to engage said toothed formation, and for that purpose having an operative connection with the carrier and a part to be moved by the condition of tension upon the thread, into partial or complete engagement with said toothed formation, the position of partial engagement permitting rotation of the thread package in a direction of unwinding the thread only, and the position of total engagement preventing rotation of the thread package in either direction upon its axis, said member being also manually movable upon its said operative connection into a position of complete disengagement with said toothed formation.
